US0D1026390S

(12) **United States Design Patent** (10) **Patent No.:** **US D1,026,390 S**
(45) **Date of Patent:** **** May 7, 2024**

(54) **VACUUM LIFT FOR GOODS**

(71) Applicant: **MQUIP GROUP INC.**, Burlington (CA)

(72) Inventor: **James Allen Douglas Reid**, Ontario (CA)

(73) Assignee: **MQUIP GROUP INC.**, Burlington (CA)

(**) Term: **15 Years**

(21) Appl. No.: **35/515,106**

(22) Filed: **Jul. 5, 2022**

(80) **Hague Agreement Data**

Int. Filing Date: **Jul. 5, 2022**

Int. Reg. No.: **DM/223082**

Int. Reg. Date: **Jul. 5, 2022**

Int. Reg. Pub. Date: **Sep. 9, 2022**

(51) **LOC (14) Cl.** **12-05**

(52) **U.S. Cl.**

USPC **D34/28**

(57) **CLAIM**

The ornamental design for vacuum lift for goods, as shown and described.

DESCRIPTION

2. Vacuum lift for goods

2.1 : Perspective

2.2 : Top

2.3 : Front

2.4 : Back

2.5 : Left

2.6 : Right

2.7: Bottom

Vacuum lifting device.
